DISTRICT OF COLUMBIA.

COMBINATION MOUNT FOR MACHINE GUNS.

Application filed October 9, 1925. Serial No. 61,614.

(GRANTED UNDER THE ACT OF MARCH 3, 1883; 22 STAT. L. 635.)

The invention described herein may be used by the Government, or any of its officers or employees in prosecution of work for the Government, or by any other person in the United States, without payment to me of any royalty thereon, in accordance with the act of March 3, 1883.

This invention relates to a combination mount for machine guns.

With the advent of aircraft in warfare and the employment of machine gun fire in combating it, it becomes necessary to devise a mount which while embodying all the essential requirements of the mount when used against ground targets, may, on a moment's notice, be converted into a mount adapted to permit high angle firing against aerial targets with proper aiming and manipulation of the gun. This dual purpose must be accomplished by combining to the greatest possible extent the requirements of simplicity, compactness, and light weight, with the characteristics of rigidity and stability, convenience in adjusting the mount to its firing position and folding it for transportation and provision for accurate adjustment of the gun in azimuth and elevation.

For firing against ground targets, a gun must be capable of being operated from a low stable mounting for the protection of both the gun crew and advancing friendly troops, but for firing against rapidly moving aerial targets, a high mount is of prime consideration to facilitate aiming and manipulation of the gun.

To these and other ends the present invention contemplates a gun cradle whose axis of elevation is in the plane of the axis of traverse and which may be readily elevated to a substantially vertical position to mount a gun for high angle fire against aircraft. The free end of the cradle constitutes a yoke for trunnioning the gun when in this position. The yoke is offset with respect to the cradle so that when the cradle is positioned coincident with the axis of traverse the mass of the cradle will be forwardly of the gun trunnions and may tend to compensate for the rearward thrust transmitted to the mount on recoil.

The elevating mechanism which is fulcrumed adjacent the free end of the cradle

and is used in the low mounting may readily be removed if desired when the cradle is swung to the vertical to be used as an anti-aircraft adaptor.

To these and other ends, our invention consists in the construction, arrangement, and combination of elements, described hereinafter and pointed out in the claims forming a part of this specification.

A practical embodiment of the invention is illustrated in the accompanying drawings, wherein:

Fig. 1 is a view in side elevation of a mount constructed in accordance with the invention and adjusted for low angle firing;

Fig. 2 is a plan view thereof;

Fig. 3 is a view in side elevation with the cradle swung to the vertical position to be used as an anti-aircraft adaptor;

Fig. 4 is a vertical sectional view of the tripod head on the line 4-4 of Fig. 3 and

Fig. 5 is a horizontal sectional view on the line 5-5 of Fig. 4.

Referring to the drawings by numerals of reference:

The mount which may conveniently assume the form of a tripod consists of a socket member 5 to which may be adjustably secured the customary legs 6.

Mounted in the socket is a pintle 7 on the lower end of which may be threaded a nut 8 serving to hold the pintle against removal and bearing against a spring 9 which compensates for wear. A friction clamp 9 mounted in the socket and having a hand wheel 10 is operable to prevent rotational movement of the pintle.

The head of the pintle is provided diametrically with an upstanding lug 11 to which are secured on each side externally serrated discs 12-12. An axis pin 13 headed at one end and screw threaded at the other end passes through the lug and discs and serves to mount for movement in elevation a cradle 14. The cradle comprises a pair of similar plates 15-15 rigidly connected at their rear portions by spacers 16, their forward portions being resilient and provided with serrated discs 17-17 adapted to engage the corresponding discs 12 on the lug 11 when the cradle plates are drawn together by means of a jamming handle 18 threadable on the end of the axis pin 13. A

washer or ring 19 may be pinned on the extremity of the axis pin to prevent loss of the jamming handle.

The cradle plates 15 are formed forwardly of the axis pin 13 and on their upper sides with ears 20—20 preferably fitted with apertured bushings 21 between which may be placed the trunnion block of the machine gun 22 secured by the customary handled trunnion pin 22'. This arrangement throws the weight of the gun forwardly of the cradle trunnions and results in offset of thrust or whip of the gun, both of which materially assist in stabilizing the mount.

15 The rear end of the gun may be supported in the usual manner by an elevating screw 23 carried in a housing 24 which is pivoted between the cradle plates by means of a pair of short headed bolts 25 threaded in the plates. These bolts may be readily unloosed to remove the elevating unit when the cradle is to be permanently used as an anti-aircraft adaptor.

25 The free end of the cradle constitutes a yoke 26 provided with apertured bushings 27 to form bearings for the trunnion pin when the cradle is swung to the vertical in using it as an adaptor. In this adjustment it is desirable that the trunnion be located 30 in the plane of the axis of the pintle and such a positioning is permitted by the serrated joint which provides a positive lock for holding the cradle at all angles of elevation.

35 The yoke 26 in which the trunnion bearings 27 are situated is preferably offset with respect to the cradle so that when used to mount the gun for firing against aircraft the mass of the cradle will be forwardly of the 40 gun and trunnions and may tend to compensate for the rearward thrust transmitted to the mount on recoil. This arrangement, among other things, facilitates traversing of the gun and insures a more stable mount.

45 If desired the offset yoke may be swivelly mounted on the cradle instead of being integral therewith.

An azimuth scale ring 30 encircling the head of the pintle is rotatably mounted in a 50 groove in the upper face of the socket member and may be secured in adjusted position by means of a clamp 31. The scale face of the ring is at an angle of 45° to permit ready reading of the scale.

55 We claim:

1. A mount for machine guns embodying a socket member, a pintle mounted therein and provided diametrically with an upstanding lug having annular serrated sides, a 60 headed axle pin passing through said lug, a combination cradle including side plates rigidly connected at their rear portion and having a resilient forward portion mountable on the axle pin, serrated discs on said 65 forward portions adapted to engage the ser-

rated lug, a jamming handle on the axle pin for contracting the cradle plates to engage the serrations, trunnion bearings in the forward upward sides of the cradle plates, an elevating mechanism pivoted adjacent the 70 free end of the cradle, trunnion bearings in the free ends of the cradle plates, said ends being offset so that when their bearings are coincident with the axis of the pintle the cradle may tend to compensate for the thrust 75 transmitted to the mount.

2. A mount for machine guns embodying a socket member, a pintle mounted therein and provided diametrically with an upstanding lug having annular serrated sides, a 80 headed axle pin passing through said lug, a combination cradle including side plates mountable on the axle pin, serrated discs on said forward portions adapted to engage the serrated lug, a jamming handle on the axle 85 pin for contracting the cradle plates to engage the serrations, trunnion bearings in the forward upper sides of the cradle plates, an elevating mechanism pivoted adjacent the free end of the cradle, and trunnion bearings 90 in the free end of the cradle plates.

3. A mount for machine guns embodying a socket member, a pintle mounted therein, a headed axle pin passing through the upper 95 end of the pintle, a cradle including side plates mountable on the axle pin, a jamming handle on the pin for holding the cradle in position of elevation, means for supporting a gun for low angle fire on the cradle, trunnion bearings in the free ends of the cradle 100 plates for supporting a gun for high angle fire, said free ends being offset so that when their bearings are coincident with the axis of the pintle the cradle may tend to compensate for the thrust transmitted to the mount. 105

4. A mount for machine guns embodying a socket member, a pintle mounted therein, a headed axle pin passing through the upper 110 end of the pintle, a cradle including side plates mountable on the axle pin, a jamming handle on the pin for holding the cradle in position of elevation, means for supporting a gun for low angle fire on the cradle, trunnion bearings in the free ends of the cradle 115 plates for supporting a gun for high angle fire.

5. A mount for machine guns embodying a support, a cradle pivoted to the support for movement in elevation and having its free end offset, means for holding the cradle 120 in adjusted position, means including an elevating mechanism for mounting a gun on the cradle for low angle fire, and trunnion bearings in the offset free ends of the cradle for mounting a gun for high angle fire, said 125 cradle being dimensioned so that when the bearings are coincident with the axis of the support it will substantially compensate for the reaction due to recoil in the gun trunnions.

6. A mount for machine guns embodying a support, a cradle pivoted to the support for movement in elevation and having its free end offset, means for holding the cradle in adjusted position, means for mounting a gun on the cradle for low angle fire, and means whereby the gun may be 15 mounted for high angle fire on the free end of the cradle.
- 5 7. A mount for machine guns embodying a
